UNITED STATES PATENT OFFICE.

GEORGE MYRICK AND WILLIAM ROLLER, OF PHILADELPHIA, PENNSYLVANIA, ASSIGNORS TO MYRICK, ROLLER & HOLBROOK, OF SAME PLACE.

DESIGN FOR A SPOON OR SIMILAR ARTICLE.

SPECIFICATION forming part of Design No. 19,709, dated March 18, 1890.

Application filed October 8, 1889. Serial No. 326,328. Term of patent 7 years.

To all whom it may concern:

Be it known that we, GEORGE MYRICK and WILLIAM ROLLER, both citizens of the United States, residing at the city of Philadelphia, in the county of Philadelphia and State of Pennsylvania, have invented a certain new and original Design for a Spoon or Similar Article, of which the following is a specification, reference being had to the accompanying drawing, which illustrates, in front elevation, a metal spoon having an ornamental foliated design in bold relief and a sunken ground around about the same.

The leading feature of our design for a spoon or similar article is a foliation or ornamental configuration displayed in bold relief and with a sunken ground adjacent to the foliated parts or ornamental configurations in the article or novelty.

Referring to the drawing, A is the sunken ground below the general plane of the spoon or similar article, and which may or may not conform to the general contour of the article.

B is the foliated part or ornamental configuration displayed in bold relief within the field or sunken ground of the article; and the two features above mentioned, which constitute the design, not only greatly enhance the value of the article or novelty, but give thereto a pleasing and ornamental effect.

Having thus described our design, what we claim as new, and desire to secure by Letters Patent, is—

The design for a spoon, fork, &c., substantially as herein described and shown.

In witness whereof we have hereunto set our signatures in the presence of two subscribing witnesses.

GEORGE MYRICK.
WILLIAM ROLLER.
